PNEUMATIC POLISHING WHEEL

Clotaire Mary, Paris, France

Application May 29, 1937, Serial No. 143,709
In France May 20, 1938

1 Claim. (Cl. 51—192)

The invention has for its object improvements in pneumatic polishing wheels.

As is known, there already exist polishing wheels comprising a pneumatic drum surrounded at its periphery by an abrasive annular band, the inflation of the inner drum determining the manner of working on the work piece. But said drums generally have two lateral metal annular parts which retain the medial rubber portion which is itself of relatively small thickness, so that during operation there is a deformation of the medial peripheral band and the apparatus can only be used in practice for working parts of rounded or convex shape and cannot serve for working on plain surfaces and, a fortiori on concave surfaces.

The improvements which are the object of the invention aim at enabling pneumatic wheels of this kind to be used for all polishing work on flat, or even concave surfaces. For this purpose, the resilient or rubber part of the drum forms both the medial part and the two annular side parts of the pneumatic drum, the metal side hoops which serve for holding said resilient part only extending to some distance from the outer periphery and consequently do not hinder the work over the whole width of the latter. On the other hand, the resilient part is made of relatively thick rubber, only permitting a slight deformation of the working surface. It is the inner pressure of inflation which determines the holding and if desired the deformation of the abrasive band, which in this case has the whole width of the drum.

In its construction, the rubber part forming the resilient drum advantageously comprises a central thick portion preferably made of pure gum and two more rigid lateral rubber portions, for example made of rubber coated fabric, so as to ensure the correct maintenance of the annular shape of the drum, while permitting a certain expansion and a relative flexibility of the medial portion.

The accompanying drawing illustrates, by way of example, one embodiment of the improved pneumatic polishing wheel device which is the object of the invention. The single figure of said drawing is the vertical section of said wheel.

As seen in said drawing, the device comprises an annular rubber part *a*, of which the central portion *a*¹ is relatively thick and made of pure gum for example, whereas the two side portions *a*² are of more rigid rubber and are formed for example by a plurality of thicknesses of rubber coated fabric. Said part *a* is fixed on either side

by means of bolts *b* and of inner circles *b*¹ to side cheeks *c*, which are fixed on the other hand to the hub *d* by means of bolts *e* with the interposition of plastic joints *f*, and which are of such diameter that their edge only extends to some distance from the outer peripheral surface of the resilient part *a* so that it can never bear on the work piece.

A valve such as *g* mounted in one of the cheeks *c*, permits of the inflation of the annular space between the hub *d*, the cheeks *c* and the resilient part *a*. An inner tube can be provided inside the drum to ensure a better sealing. The pneumatic chamber can be made in one piece, the resilient part *a* being in form of closed torus.

Around the resilient part *a* is placed the annular abrasive band *h* consisting of paper or of fabric carrying on the outside the abrasive material. Said abrasive band is mounted on the drum before its inflation, and when the inflation has been effected it is held in position by said inflation.

When the inflation of the drum is slight and consequently the abrasive band remains flat, the wheel can operate perfectly flat; it can even come somewhat flattened on the operative portion and expand over the latter.

Owing to the setting back of the cheek *c* relatively to the outer surface of the resilient part *a* and of the abrasive band, said cheeks can never bear on the work piece, thereby enabling the drum to be used over the whole of its width.

The inner pressure or air of the drum, combined with the mechanical application pressure of the wheel on the work piece, will be suitably determined according to the work to be effected and the nature of the material to be polished.

The wheel thus constructed can be used, either on machines having fixed frames, or on portable hand machines, or on rolling machines for polishing flat surfaces of all kinds, made of metal, of wood, of marble, of natural or artificial stones, etc., or for polishing concave surfaces, or mounted at the end of a flexible transmission, or on a polishing head, etc.

Abrasive annular bands having slightly different diameters can advantageously be used with said wheel. With a reduced inflation the smallest diameter of band will be used and said band as well as the wheel can expand over the surface to be worked. By using an abrasive band of greater diameter, it will be possible, by considerably inflating the drum, to cause a certain bulging of its outer surface and to thus operate with the middle of said surface.

The changing of the abrasive band is very easily effected by deflation, then by inflation of the drum.

Said pneumatic grinding wheel has a large number of advantages amongst which the following may be cited:

1. Smoothness in the contacting of the wheel with the part to be polished, thereby enabling the wheel to be applied in the portable form, on a metal sheet or part without fear of deterioration.
- 10 2. Possibility, with a single wheel, of using polishing bands made of abrasive fabric of all kinds of grain, from the coarsest for trimming, to the finest for polishing, and of changing said band in a few moments, and the possibility likewise of using polishing bands made of buff leather which the user himself can cover or not, with abrasive material.
- 15 3. Possibility of using the wheel with slight inflation so as to polish all more or less deformed parts, of a metal sheet, of a floor, of a mould board of a plough, etc., or with a greater inflation so as to bulge the operative surface and thus work on the middle of the latter.

It is obvious that the invention is not limited to the constructional details which have been

described and illustrated above and that it is capable of any modifications.

What I claim and desire to secure by Letters Patent of the United States is:

A pneumatic polishing wheel, comprising an annular drum having a comparatively thick and elastic central portion consisting of gum and extending over the entire width of the wheel, and side portions situated at both sides of said central portion, said side portions consisting of rubber coated fabrics and being less thick and less elastic than said central portion, an annular abrasive band covering said central portion, two metallic side cheeks situated at a distance one from the other and having annular outer end portions and inner end portions, the diameters of said outer end portions being substantially smaller than the diameter of said central portion, means connecting the side portions of said drum with the outer end portions of said side cheeks, a rotary shaft connected with the inner end portions of said side cheeks, and means carried by one of the side cheeks for supplying air under pressure into the space between said side cheeks and said drum.

CLOTAIRE MARY.
